LIQUID DISPENSER UNIT

Robert B. Koch, 7055 Fenkell Ave., Detroit 38, Mich.

Filed Dec. 31, 1962, Ser. No. 73,008

Term of patent 14 years

(Cl. D58—17)

FIG. 1

FIG. 2

FIG. 3

FIG. 1 is a front elevational view of a liquid dispenser unit showing my new design having a container and detachable liquid bellows-type dispensing element showing the dispensing element in expanded condition;

FIG. 2 is a side elevational view thereof with the dispensing element in compressed condition; and

FIG. 3 is a top plan view of the same.

I claim:

The ornamental design for a liquid dispenser unit, substantially as shown and described.
